C. G. FETTE,
DUSTLESS ASH SIFTER,
APPLICATION FILED OCT. 29, 1918.

1,347,151.

Patented July 20, 1920.

UNITED STATES PATENT OFFICE.

CHARLOTTE G. FETTE, OF SHELTON, CONNECTICUT.

DUSTLESS ASH-SIFTER.

1,347,151.

Specification of Letters Patent. Patented July 20, 1920.

Application filed October 23, 1918. Serial No. 259,369.

To all whom it may concern:

Be it known that I, CHARLOTTE G. FETTE, a citizen of the United States, residing at Shelton, in the county of Fairfield, State 5 of Connecticut, have invented certain new and useful Improvements in Dustless Ash-Sifters; and I do hereby declare the following to be a full, clear, and exact description of the invention, such as will enable 10 others skilled in the art to which it appertains to make and use the same.

The invention relates to a sifter and more particularly to the class of dustless ash sifters.

15 The primary object of the invention is the provision of a sifter of this character, wherein the sifting is done within a reticulated rotary cylinder mounted on and driven by an axial shaft, and the latter has

20 V-shaped elbows in its length within the cylinder so as to agitate the ashes during the operation thereof.

A further object of the invention is the provision of a sifter of this character, which 25 possesses simplicity in construction, durability, efficiency in operation and also one which may be manufactured at a minimum expense.

With these and other objects in view, the 30 invention consists in the features of construction, combination and arrangement of parts as will be hereinafter fully described, illustrated in the accompanying drawing and pointed out in the claim hereunto appended.

35 In the accompanying drawing:

Figure 1, is a front elevation of a sifter constructed in accordance with the invention.

40 Fig. 2, is an end elevation thereof.

Fig. 3 is a vertical transverse sectional view on the line 3—3 of Fig. 1.

Fig. 4, is a vertical longitudinal sectional view through the sifter.

45 Fig. 5, is a fragmentary detailed sectional view through the sifter cylinder showing the manner of fastening the cover section closed.

Fig. 6, is a fragmentary transverse sectional view showing in detail the manner of fastening the cover to the casing closed.

Referring to the drawing in detail, A, 50 designates a casing preferably of box-like formation having a forwardly arched cover or lid B connected to the back wall of the

casing A, for vertical swinging movement to open or close the same through the medium of strap hinges 10, while at the front of the casing A near opposite ends thereof are snap spring catches 11 which engage the 60 cover or lid B for latching the same closed.

Formed in the lower portion of the casing A is a drawer space which opens through the front side of the casing and slidably receives therein a drawer 12 65 adapted to catch ashes when the sifter is operated. The drawer at the front is fitted with loop handles 13 for permitting the convenient opening and closing of said drawer. The front of the drawer snugly 70 and detachably fits the opening of the drawer space in the casing A to avoid the escape of ashes during the operation of the sifter.

75 Inferiorly of the casing A and mounted on the end walls thereof approximately centrally of the same, are substantially U-shaped bearings 14 in which is journaled a rotatable shaft 15, the end 16 of which is passed through the adjacent end wall of the casing A exteriorly thereof and carries a movable crank handle for the manual rotation of the shaft 15 as will be obvious.

80 Carried upon the shaft 15 within the casing A is a rotary cylinder formed with a reticulated or wire meshed cylindrical body 18 and circular ends 19 having centrally passed therethrough the shaft 15, the body 18 being fixed to the ends 19 in any suitable manner, while these ends 19 concentrically 85 of the shaft 15 have fixed thereto collars 20 in which are mounted set screws 21 adapted to bite into the shaft 15 for the fastening of the ends 19 thereon.

85 The body 18 includes a door section 22 supported upon hinges 23 and held closed through the medium of spring clips 24 engaging suitable keepers on the body 18, and into this cylindrical sifter is placed ashes to be sifted, the ashes being introduced on the opening of the cover or lid B and the door 22, as will be apparent.

100 The cinders and unspent fuel will be retained in the cylinder while the ashes will be deposited in the drawer during the operation of the sifter. The shaft 15 is bent on itself or distorted to form intermediate and outer reversely set or extended sub-triangular portions or elbows 25 and 26 respectively, which constitute agitator por- 105 110

tions within the sifter cylinder for breaking up the masses of ashes contained therein during the operation of the sifter.

These elbows are V-shaped bends formed 5 in the shaft 15, and it will be observed from Fig. 3 that the intermediate bend 25 rises from the line of the shaft while the two endmost bends 26 depend from said line and stand in the plane of the pendant crank 10 handle; hence there is a preponderance of weight tending to hold the cylinder with its door at the top, so that when the casing door is open the cylinder door may be reached and opened. Moreover, the angles 15 of the bends in the agitator shaft stand about midway between the line of the shaft and the reticulated cylinder, and therefore when the latter is rotated the material therein is agitated by the angles of the 20 bends which dip into the material more or less as the material is deep or shallow within the cylinder; and when the crank handle descends the angles of the two endmost bends 25 agitate the mass, whereas the angle of the intermediate bend agitates such mass as the handle ascends—therefore during each 30 complete revolution the endmost bends dip partly into and pass through the mass once along lines near the heads of the cylinder and the intermediate bend dips once into 35 this mass on a line substantially at the mid-length of the cylinder. The action of a sifter of this kind is that the mass lying within the cylinder is carried partway up its ascending side, and as fast as its angle of repose becomes sufficiently steep the upper portion of the mass tumbles back constantly to the bottom of the cylinder which is now mostly clear, and falls through it into the 40 receptacle below. Said tumbling portion includes everything from the finest dust to

the coarsest particles, but the weight of the latter causes them to move more quickly, and the result is that they fall across the mass and reach the bottom of the cylinder 45 first. As they are too large to pass through the screen, they repeat the operation again and again, unless they become broken up into smaller particles. Therefore an agitator within a rotary sifting screen adapted 50 for use on ashes, especially where its projections extend only partway from the axis to the screen, has the effect of retarding the fall of said larger particles so that they are more quickly broken up and complete disintegration of the mass effected. I find that it is not necessary to have the agitator extend to or even nearly to the screen 55 surface, because the fine dust readily passes therethrough without the necessity for agitation.

What is claimed is:

A sifter of the type described, comprising a screen cylinder, a shaft fixedly mounted through the centers of its ends and 65 formed between the latter into V-shaped bends all standing in a single plane and whereof one projects in one direction at the midlength of the cylinder and others near the ends thereof project in the opposite direction, the angles of said bends standing approximately midway between the axis 70 and the wall of the cylinder, and means for supporting the extremities of said shaft and for turning it to rotate the cylinder. 75

In testimony whereof I affix my signature in the presence of two witnesses.

MRS. CHARLOTTE G. FETTE.

Witnesses:

OMER FORTIER,
J. ALMANDINGER.
